UNITED STATES PATENT OFFICE.

FRANK M. STEINER AND WALTER S. GRAVES, OF MINNEAPOLIS, MINNESOTA, ASSIGNORS TO STEINER SALES COMPANY, OF SALT LAKE CITY, UTAH, A CORPORATION OF UTAH.

TOWEL CABINET.

Application filed September 5, 1922. Serial No. 586,220.

To all whom it may concern:

Be it known that we, FRANK M. STEINER and WALTER S. GRAVES, citizens of the United States, residents of Minneapolis, 5 Hennepin County, Minnesota, have invented certain new and useful Improvements in Towel Cabinets, of which the following is a specification.

The object of our invention is to provide 10 a cabinet adapted to contain a reserve roll of clean toweling in addition to the one that is being used to the end that the cabinet will not require as frequent attention by the janitor as it would if equipped with only one 15 towel roll.

A further object is to provide a cabinet in which provision is made for convenient access to the towel rolls.

A further object is to provide separate 20 compartments for the soiled toweling to prevent the soiled portion of one towel becoming twisted or entangled with the corresponding portion of the other towel and making it difficult to remove one soiled 25 towel without also pulling out the soiled end of the clean towel in use, and thereby unfolding and tangling both towels.

A further object is to arrange the compartments and toweling so that the soiled 30 towel will drop in folds and fold up as it falls into the soiled towel compartment, thus making it more convenient for the janitor and laundry driver to handle, and more economical at the laundry to wind and 35 prepare for washing.

A further object is to provide means whereby the reserve towels must be brought 40 in contact with the measuring and stopping device when the user places it in position for use, the contact being made in such manner that the measuring and stopping device will operate.

A further object is to provide improved 45 means to be actuated by the user for locking the clean towel roll and limiting the movement thereof when a pull is applied to the clean toweling.

Other objects of the invention will appear 50 from the following detailed description.

The invention consists generally in various constructions and combinations, all as

hereinafter described and particularly pointed out in the claims.

In the accompanying drawings forming 55 part of this specification,

Figure 1 is a vertical sectional view through a towel cabinet embodying our invention.

Figure 2 is a side view of the cabinet.

Figure 3 is a vertical sectional view on 60 the line 3—3 of Figure 4.

Figure 4 is a sectional view on the line 4—4 of Figure 3.

Figure 5 is a detailed sectional view of the locking device.

Figure 6 is a detailed sectional view showing a modified form of locking device in its normal position.

Figure 7 is a detailed sectional view of the locking device in its release position.

Figures 8 and 9 are detailed sectional views of another form of locking device shown in its normal and release positions.

Figures 10 and 11 are detailed sectional views of still another form of locking device shown in its normal and release positions.

In the drawings 2 represents the side walls of the cabinet having suitable supporting legs 3, a rear wall 4 and a front 80 wall 5. In the top, the cabinet has an opening 6 through which the user may have access to the clean towel. In the rear of this opening we arrange a clean towel carrier 7 eccentrically mounted in the side wall of the cabinet on a pivot 8.

This carrier has two compartments or chambers 9 and 10 separated by a hinged gate 11. In these compartments rolls of clean toweling 9^a and 10^a are placed, the 90 upper compartment being adjacent to a feed roll 12 mounted in bearings in the upper portion of the carrier and having a friction surface 13 over which the clean towel passes. A plate 14 is preferably hinged to the top 95 of the cabinet and depends in front of the feed roll resting upon a stop 15 and normally concealing and protecting said feed roll and in this plate a mirror 16 is preferably mounted for the convenience of the users of 100 the cabinet. A gap is provided between the lower portion of the carrier 7 and the front

- wall of the cabinet through which gap the soiled towel is directed into the lower portion of the cabinet. A guide wall 17 is provided at the front of the cabinet for directing the soiled portion of the towel therein and this wall also serves as a stop to prevent the hands of the user from moving down too far and withdrawing an unnecessary length of towel from the roll.
- 10 A stop pin 18 is mounted in the peripheral surface of the feed roll. A yoke 19 is pivoted at 20 on the wall of the cabinet and has arms 21 and 22 thereon. The arm 21 is normally engaged with the pin 18 to check revolution of the feed roll. A push rod 23 is pivotally connected with the yoke 19 and projects out through the wall of the carrier and has a push button 24 thereon and is normally held in its retracted position by a spring 25. When this push rod is pushed in by the user the yoke 20 will be rocked and disengaged from the pin 18 and thereupon the user may pull the towel and revolve the feed roll. Should the user immediately release the push rod the spring will return it to its normal position and engage the pin 18 and check the feed roll after one revolution but should the user continue pressure on the push rod after releasing the yoke as indicated in Figure 5 the pin 18 will engage the arm 22 and revolution of the feed roll will be checked before the desired length of towel has been delivered. It is necessary, therefore, for the user to immediately release the push rod if he wishes to obtain a suitable length of towel for wiping purposes.
- In the lower portion of the cabinet we provide two soiled towel compartments 26 and 27 separated by a vertical partition 28.
- 40 The towel as it is delivered to these compartments falls in folds as indicated in Figure 1 and for the convenience of the laundry man we prefer to divide the soiled toweling allowing it to accumulate in folds in the separate compartments instead of depositing both rolls in one compartment. Access to these soiled towel chambers or compartments is obtained through a suitable door 29 in the side wall of the cabinet. For the purpose of automatically directing the soiled toweling to these different compartments we provide a gate 30 supported by a horizontal pivot 30^a in the side wall of the cabinet preferably within a suitable box or casing 31.
- 50 A yoke 32 is mounted on the pivot 30^a and has a slot 33 therein provided with cam surfaces 33^a and 33^b. A link 34 projects into the casing 31 and has a pin 35 at one end projecting into the slot 33. At the other end the link 34 is pivotally connected with the towel carrier 7 at 36. The gate 30 is shifted back and forth by the movement of the towel carrier in the following manner. Figure 1 represents the normal position of the carrier and gate with the soiled towel being delivered to the forward compartment 26. Assuming now that this compartment has been filled and it is desired to direct the soiled towel of another roll to the other compartment 27 the user will swing the carrier from the position shown in Figure 1 forward to the position shown in Figure 3. This movement of the carrier will raise the pivotal connection of the link 34 with the carrier from the point shown in Figure 1 to the position in Figure 3 and this movement will raise the pin 35 at the lower end of the link 34 up into contact with the cam surface 33^a of the yoke 32 and swing said yoke on its pivot and move the gate 30 from the full line position in Figure 1 to the full line position in Figure 3 and thereupon the opening to the front wall towel compartment will be closed and the rear soiled towel compartment opened. The person in charge of the cabinet will then place the reserve towel roll in the upper compartment and pass its loose end over the feed roll, then raise the carrier to a vertical position and the cabinet is ready for use again, the soiled towel falling into the base of the cabinet being directed by the gate 30 into the rear compartment. It will be understood that when the person in charge of the cabinet raises the carrier from the position shown in Figure 3 to its upright position that the gate 30 will not be affected by such movement, the pin 35 moving to the lower portion of the slot in the yoke without engaging either of the cam surfaces or moving the yoke but upon the next movement of the carrier, the pin 35 will engage the cam 33^b and the position of the gate will again be changed and the passage opened to the forward towel compartment. In this way we are able to keep the soiled towels separate for convenience in handling by the laundry man without any attention on the part of the person in charge of the cabinet and there is no manual adjustment of gates or mechanism required to direct the soiled towel to the different compartments.
- In Figures 6 and 7 we have shown a modified construction of the locking device. The feed roll 37 is shown having a socket 38 therein and a spring 39 and a plunger 40 that is normally held in its projected position by the spring 39. A stop 41 is provided on the wall of the cabinet in the path of the plunger pin and a push pin 42 is mounted in the wall 43 normally retracted by a spring 44 and adapted to be pressed in by the user to disengage the plunger from the stop 41. As soon as this has been done the user may pull the towel and revolve the roll one revolution. Then the plunger will strike the stop 41 and be arrested. If the user should keep his finger on the push pin the plunger will strike the pin at the end of the first revolution and movement of

the feed roll be checked. In Figures 8 and 9 we have shown a modification which consists in mounting a dog 45 in the feed roll normally held in its projected position by a spring 46 to engage the stop 41. This dog is moved out of engagement with the stop by pressure on the push pin as described with reference to Figures 6 and 7.

In Figures 10 and 11 we have shown another modification which consists in providing a slide 47 having a slot 48 therein to receive the shaft 49 of the feed roll. A spring 50 normally holds the slide in its projected position. Stops 51 and 52 are provided on the slide and a pin 53 is mounted in the end of the feed roll in position to normally contact with the stop 51 and check movement of the roll. When the slide is pushed in to the position shown in Figure 11 and immediately released after the user has exerted a pull on the towel, the stop 51 will be moved out of the path of the pin 53 and the feed roll may make a complete revolution, but should the user continue to press in on the slide the feed roll will be checked at the end of a half revolution by contact with the stop 52. It will therefore be necessary for the user to release the slide if he wishes to obtain a full wiping length of the towel.

We claim as our invention:

1. A towel holder comprising a carrier adapted to receive rolls of clean towel, means over which the web of clean towel is delivered to the user, said carrier having a tilting movement to allow access thereto for the deposit of clean rolls of towel therein, said holder having soiled towel compartments below said carrier and means positioned by the movement of said carrier for closing the passage to one compartment and opening the passage to the other compartment.

2. A towel holder comprising a carrier adapted to contain a plurality of clean towel rolls, a feed roll over which the clean towel is delivered to the user, said carrier having a limited movement to allow access to the clean towels, said holder having soiled towel compartments below said carrier, one for each roll of toweling, and means positioned by the movement of said carrier for closing the passage to one towel compartment and opening the passage to the other towel compartment.

3. A towel cabinet comprising a casing having forward and rear soiled towel compartments in its lower portion and a partition between them, the upper portion of said casing having an opening for access to the clean towel, a towel carrier mounted in said casing in the rear of said opening and adapted to contain rolls of toweling one above the other, a feed roll in the upper portion of said carrier over which the clean towel is delivered to the user, a gap being

provided between the lower portion of said carrier and the wall of said casing through which the soiled towel is directed to the compartments beneath, and in which compartment the towel is delivered in horizontal folds, one upon the other, the soiled towel of one roll being directed to one towel compartment and the soiled towel of the other roll to the other compartment.

4. A towel cabinet comprising a casing having soiled towel compartments in its lower portion and an opening in its upper walls through which access may be had to the clean towel, a towel carrier in the rear of said opening having compartments for rolls of clean toweling and mounted to tilt forwardly through said opening to expose said chambers and permit the insertion of the clean rolls of towel therein, a feed roll mounted in the upper portion of said carrier and over which the clean towel is directed within reach of the user, said carrier being normally in a vertical position within said casing when the cabinet is in use, an opening being provided between the lower portion of said carrier and the wall of said casing through which the soiled towel is directed to said soiled towel compartment.

5. A towel cabinet comprising a casing having an opening in its upper walls through which access may be had to the clean towel, the lower portion of said cabinet having compartments for the soiled towel, a towel carrier mounted in said casing in the rear of said opening and from which the towel is delivered to the user, there being compartments in said carrier for a plurality of rolls of toweling, a gate for closing the passage to one or the other of said soiled towel compartments in the bottom of said casing, and mechanism actuated by the movement of said carrier for positioning said gate to close the passage to one soiled towel compartment and open the passage to the other compartment.

6. A towel cabinet comprising a casing having an opening in its upper front wall, and a soiled towel compartment in its lower walls, a clean towel carrier pivoted within said casing in the rear of said opening and adapted to tilt forwardly through said opening, said carrier having chambers therein for rolls of clean toweling, a shelf between said compartments hinged to swing forwardly upon the carrier being tilted forwardly whereby to permit movement of the rear roll of toweling into the forward compartment, accessible when said carrier is tilted forwardly, and means over which the web of clean toweling is fed to said opening and the user.

7. A towel cabinet, comprising a casing having opening in its upper front walls, a towel carrier supported in said casing in the rear of said opening, and having chambers

4

for rolls of clean toweling, a shelf between said compartments hinged to swing forwardly upon the carrier being tilted forwardly whereby to permit movement of the rear roll of toweling into the forward compartment, said carrier being adapted to move forwardly through said opening for access to said chambers and the clean towel-

ing, a feed roll mounted in the upper portion of said carrier, and over which the web ¹⁰ of clean towel passes to said opening and the user.

In witness whereof, we have hereunto set our hands this 1st day of September 1922.

FRANK M. STEINER.
WALTER S. GRAVES.
